R. C. DOLLE

SHIPPING CONTAINER AND DISPLAY DEVICE

Filed Oct. 31, 1923

Fig. 2.

ROBERT G. DOLLE

Inventor

Attorney

UNITED STATES PATENT OFFICE.

ROBERT C. DOLLE, OF CINCINNATI, OHIO.

SHIPPING CONTAINER AND DISPLAY DEVICE.

Application filed October 31, 1923. Serial No. 672,007.

To all whom it may concern:

Be it known that I, ROBERT C. DOLLE, a citizen of the United States of America, and a resident of Cincinnati, in the county 5 of Hamilton and State of Ohio, have invented a new and useful Improvement in a Shipping Container and Display Device, of which the following is a specification.

This invention relates to containers for 10 use in shipping, displaying and storing water plants and plants of the variety requiring a constant supply of water.

An object of my invention is to provide a container that is adaptable for use in 15 shipping water plants.

Another object is to provide containers of this type, a number of which may be secured together, to form a simple unit for handling and shipping.

20 These and other objects are attained by the means described herein and disclosed in the accompanying drawings, in which;

Fig. 1 is a perspective view of a group 25 of containers of my invention, showing the manner of mounting and securing them for shipment.

Fig. 2 is a cross sectional view, taken on a line 2—2 of Fig. 1.

The device comprises a substantially 30 rectangular sheet metal container 3, carrying a flange 4, around the edges thereof adjacent the base 5. The flange 4 extends beyond the base 5 and provides protection therefor and the base 5 and flange 4 of one 35 container provides a close fitting cover for a second such container when placed upon the second container. Suitable fastening means such as rivets 7 may be used to secure the flange 4 upon the walls 6 of the 40 container. The upper edges 8 of the walls 6 of the containers are inwardly turned about stay rods 9 for providing a strong smooth edge; ventilating holes 100 are located in the upper portion of the walls 6. A 45 suitable flange lid 10 serves as a closure for the container and may be provided with an angular bracing strip 11 along its inner side and longitudinally central thereof. Each container 3 is provided at its opposite 50 ends with suitable handles 12.

As a means for securing a number of these 55 containers together to form a unit I have provided on each wall 6 of each container, a flanged lug 13 secured by means of rivets 14. The lugs 13 are uniformly mounted on each container 3 so that perforations 15

therethrough will register. The lid 10 carries lugs 16, having perforations 17 adapted to register with perforations 15 in lugs 13. Rods 18 having an angular extension or 60 flange 19 at one end and having a threaded end 20 are adapted to be inserted through the perforations 15 in lugs 13 and perforation 17 in lug 16. The rods 18 are inserted through the registering perforations in the 65 lugs on the containers and the lid, the flange 19 on the rod abutting the lug on the lowermost container and the threaded end 20, extending through the lug 16 on the lid 10. A wing nut or the like 21, having 70 any suitable gripping means thereon, is then mounted on the threaded end 20 of the rod 18 against lug 16 on the lid. As nuts 21 are tightened on the rod 18, the containers are 75 tightly clamped, one upon the other and the lid 10 is also clamped upon the uppermost container. The unit thus formed may be expeditiously handled by means of the handles 12 on the containers.

Attention is directed to the fact that a 80 device has thus been provided wherein water plants may be packed with sufficient water to sustain them and wherein necessary ventilation is attained. Additional water may be put into the containers thru the 85 ventilating holes by means of a hose or sprinkling can, so that the plants may be shipped or stored for indefinite periods without necessitating the disassembling of the unit. By supplying rods 18 in various 90 lengths, the units may be built up to comprise any desirable number of containers, one lid 10 being required for each unit. A single container may be used in stores for 95 display purposes while the remaining units, with growing plants therein, may be stored away in a small space.

What I claim is:

1. In a combined shipping, storage and 100 display device for water plants the combination of individual containers, each capable of independent display use, and each comprising side walls having perforations adjacent their upper edges for providing ventilation and permitting replenishment of the water supply, a stay rod 105 upon the inner edge and extending about the upper edge of each container and over which stay rod the upper edges of the side walls are turned, a peripheral depending flange at its bottom arranged to extend 110 about the upper edge of the container next

below, a lid adapted to receive the upper edge of any container, and means for locking a plurality of containers and a lid upon one another.

5 2. In a combined shipping, storage and display device for water plants, the combination of a multiplicity of individual containers, each container capable of independent use and comprising side walls 10 having perforations therein and a base, the perforations in the side walls being utilized for ventilation and replenishing of plant food, a peripheral flange carried by the side walls and surrounding the base 15 of each container and arranged to extend over the upper edge of the next succeeding

container, a lid capable of being used for a closure for each container, a flanged lug mounted on the individual containers and lid, the lugs having registering perforations 20 therein, a rod insertable through the perforations in the lugs having a hook formed on one end and threads on the other end, and a winged nut mounted on the threaded end of the rod, the flanged lugs, winged 25 nut and rod constituting a means for locking the individual containers and lid together.

In testimony whereof, I have hereunto subscribed my name this 20th day of October, 1923.

ROBERT C. DOLLE.
